UNITED STATES PATENT OFFICE.

MAX HIRSCHBACH, OF YONKERS, NEW YORK.

DESIGN FOR A SLIPPER.

Application filed May 4, 1925. Serial No. 13,321. Term of patent 3½ years.

To all whom it may concern:

Be it known that I, MAX HIRSCHBACH, a citizen of U. S. A., residing at Yonkers, in the county of Westchester and State of New York, have invented a new, original, and ornamental Design for Slippers, of which the following is a specification, reference being had to the accompanying drawing, forming part thereof.

Figure 1 is a side elevation of a slipper illustrating my new design;

Fig. 2 is a top plan view thereof, and

Fig. 3 is a front end elevation.

I claim:

The ornamental design for a slipper, as shown.

MAX HIRSCHBACH.
